J. OAKLEY.

BROACH.

APPLICATION FILED OCT. 6, 1920.

Patented July 25, 1922.

WITNESS:

A. O. Fairbanks,

INVENTOR.

John Oakley,
BY
Frank A. Cutta,
ATTORNEY.

UNITED STATES PATENT OFFICE.

JOHN OAKLEY, OF SPRINGFIELD, MASSACHUSETTS.

BROACH.

1,423,814.

Specification of Letters Patent. Patented July 25, 1922.

Original application filed June 25, 1918, Serial No. 241,748. Divided and this application filed October 6, 1920. Serial No. 415,010.

To all whom it may concern:

Be it known that I, JOHN OAKLEY, a subject of the King of Great Britain, residing at Springfield, in the county of Hampden and State of Massachusetts, have invented a new and useful Broach, of which the following is a specification.

My invention relates to improvements in tools of the drift or broach type, which are used to cut grooves, channels, slots, and the like in various objects, and consists essentially of a shank provided with cutting teeth, and equipped with a pilot ahead of such teeth, together with such other elements as may be needed or desired in order that the tools shall be complete and serviceable in every respect, all as hereinafter set forth.

This application is a divisional part of my application for Letters Patent of the United States, Serial No. 241,748, filed June 25, 1918, which eventuated in Patent No. 1,359,831, dated November 23, 1920.

The primary object of my invention is to provide a tool of this character with means to guide the same through the work in which a slot or groove has been initially cut or formed, so that the teeth of such tool shall be caused to follow with great accuracy the path of said guiding means, and thus be held to their course without liability of springing so as to tear or otherwise mar the sides of the groove or slot cut thereby, which is of the utmost importance, especially with reference to the leading teeth.

Other objects and advantages will appear in the course of the following description.

I attain the objects and secure the advantages of my invention by the means illustrated in the accompanying drawings, in which—

Figure 1 is a side elevation of the forward-end portion of a broach which embodies a practical form of my invention; Fig. 2, a top plan of the same; Fig. 3, a cross section through said broach, taken on lines 3—3, looking in the direction of the associated arrow, in Fig. 1; Fig. 4, what may be termed a side elevation of the forward-end portion of a broach which illustrates another embodiment of said invention, and, Fig. 5, what may be termed a side elevation of the forward-end portion of a broach that illustrates still another embodiment of the invention.

Similar reference characters designate similar parts throughout the several views.

The teeth and clearance passages in the broaches herein illustrated are similar to those described in and covered by the aforesaid two patents, so that no extended description of the same need herein be given.

In matters of shape, size, arrangement, and construction of the parts of my invention, it is to be understood that other modifications, in addition to those illustrated in connection herewith, may be made without departing from the nature of said invention or exceeding the scope of what is claimed, wherefore I do not desire or intend to be restricted to the several embodiments shown and described in detail.

All of the broaches illustrated in connection herewith are widening tools, that is to say, they are designed to make wider a slot previously cut in the stock, and in some cases they may also deepen such slot.

Each of the aforesaid broaches comprises a shank 1, which is provided at the forward or leading terminal with suitable means for attaching the broach to the machine, as a screw-threaded puller-head 2, the same being partially broken off in Fig. 5, a plurality of teeth which differ more or less in different broaches, and guiding means or a guiding element termed a pilot.

Mounted on the shank 1 of the first broach is a row of flat, rectangular teeth 4, and a pilot 5. There is a longitudinal, chip-clearance passage or channel 6 formed in the shank 1 on each side of that part of said shank to which the teeth 4 are attached. The teeth 4 overhang the channels 6. Said teeth are all of the same thickness and let into the shank in such a manner as to obtain the stepped arrangement required in broaching.

The pilot 5 is of the same width and depth as the width and depth of the original slot which the tool is designed to widen, and is located on the shank 1 in advance of the row of teeth 4, and in the central, longitudinal plane of said row. The pilot 5 is formed on the outer end of a plug 7 which fits within a recess in the shank, and is secured therein by a transverse pin 8 passing through said shank and plug.

The central portions of the cutting edges of the teeth 4, which are in direct line with

the pilot 5, do no cutting, but the outlying portions of said edges cut away the stock to widen the original slot. The chips cut by the teeth 4 pass directly into the channels 6 in the shank, and through the latter escape at the rear end of said shank. That part of the shank which directly supports the teeth 4 is no wider than the pilot 5, consequently there is nothing to divert the chips 10 from their downward courses against the beveled front edges of said teeth, as soon as said chips are cut, and into the chip-clearance channels.

It is now clear that, if this broach be applied to a piece of stock having a central opening or passage and a slot therethrough, which slot it is desired to widen, and which passage and slot correspond, respectively, to the diameter of said shank and the size of 15 the pilot 5, said shank will fit said passage and said pilot will fit said slot. Now, if the width of the teeth 4 corresponds with that of the required slot, and the depth of the rearmost tooth is equal to the depth of said 20 slot, the operation of widening is as follows: The forward end of the shank 1 is introduced into the passage and the pilot 5 into the slot in the stock, and the tool is drawn forcibly through said passage and slot, with 25 the result that the cutting edges of the teeth 4 or the portions thereof that overhang the channels in the shank progressively cut away the inner periphery of said stock both sides of said slot, forming first the inner corners 30 of the enlarged or widened slot, and working radially or outwardly until finally the wide slot complete is produced.

The pilot 5 leads and the teeth 4 follow and cut the new or enlarged slot the full 40 width and deeper and deeper the farther the tool progresses, as is clearly apparent. The chips cut by the teeth on both sides of the slot are directed by the beveled front edges of said teeth into the passages or channels 45 prepared to receive them, and said chips pass freely through said channels and finally off at the rear end of the tool.

The broach, a portion of which appears in Fig. 4, is a widening tool having three 50 rows of teeth 9 and the same number of pilots 10, although it might have more or less than three rows of teeth and three pilots. A single tooth in each of two rows and two pilots only are represented in the drawing. 55 With the triple rows of teeth and pilots three longitudinal, chip-clearance channels 11 (one only appearing in the drawing) are required, instead of two as in the other broach which has just been described. The 60 exterior faces of the pilots 10 and of the teeth 9 are convex, because this broach is designed to widen grooves or slots which require such faces, but the latter might be flat like the faces of similar members in the 65 first broach, and, contrariwise, the exterior

faces of the pilot and teeth of said first broach might be convex.

Each tooth 9 is shaped generally like an arrow-head, and arranged on the shank 1 point forward with the cleft behind. Each 70 succeeding tooth 9 from front to rear is set farther from the axial center of the shank, as in the first case and for the same reason. V-shaped channels 12 for the chips are made in the shank between adjacent ends of the 75 teeth 9 in each row, and between the foremost ends of the leading teeth and the pilots 10, so that the chips cut by said teeth pass clear of the latter on both sides into said channels and thence into the channels 11. 80

The Fig. 4 broach is designed and adapted to widen three slots in a piece of stock which is capable of receiving the shank of said broach and the pilots 10, the peripheral walls of which slots are concave. The teeth 85 9 and the pilots 10 conform in shape to the shape of the aforesaid walls, as previously observed. The middle portions of the teeth 9 or the portions thereof that are directly in line with the pilots 10 do no work, but 90 the outlying portions of said teeth or of their cutting edges remove the stock radially and widen the slots.

The broach, a portion of which appears in the last view, is an example of a spiral, 95 widening tool which includes another form of teeth and pilot. There are two, oppositely-disposed, spiral rows of teeth 13 on the shank 1 in this case, and two oppositely-disposed pilots 14 on said shank, and the 100 outer faces of said teeth and pilots are convex as in the preceding example, but there might be more or less than that number of rows of teeth and pilots, such row or rows might be straight, and the outer faces there- 105 of might be flat. There is a longitudinal channel 15, on one side of each row of teeth 13, in the shank 1, said shank has two flattened surfaces 16 upon which said teeth are mounted, and there are obliquely-transverse 110 channels 17 in said flattened surfaces between the teeth themselves and between said teeth and the pilots, each of said channels 17 opening at one end into one of said longitudinal channels. The channels 15 and the 115 flattened surfaces 16 are spiral, and said flattened surfaces have an outward incline from front to rear, longitudinally of the shank, for the purpose of giving to the teeth 13 the different required amount of projec- 120 tion, without making said teeth of different thicknesses or setting any of them into the shank, the inner faces of the teeth being beveled slightly to conform to the inclination of said surfaces. 125

In operation, the pilots 14 first enter the previously prepared slots in the stock, which slots are spiral in the present instance, and the teeth 13 follow and widen and deepen said slots, the chips passing down into the 130

branch channels 17, through the latter into the channels 15, and thence away at the rear end of the broach.

It is an advantage to employ an attachable and detachable pilot (or pilots), such as that represented in the first three views, not only because it is frequently less expensive to construct a broach with such a pilot (or pilots), but on account of the fact that the same when damaged or broken can be taken out, repaired, and replaced, or replaced with a new one, without being obliged to discard the entire broach. The manner of removing and replacing the pilot 5 will be readily understood from the drawings and hereinbefore given description.

The pilots may be integral with or permanently attached to the shank, as indicated in Figs 4 and 5 wherein no means is shown 10 for removing the pilots 10 and 14.

What I claim as my invention, and desire to secure by Letters Patent, is—

1. A broach comprising a shank provided with a row of teeth, and further provided 25 with a detachable guiding member in advance of said teeth.

2. A broach comprising a shank having longitudinal channels formed in the periphery and opening at the rear end of said shank, a row of teeth on that part of said shank which is between said channels, said teeth having outer transverse cutting edges, and a pilot, of less width than that of said teeth, on said shank ahead of the teeth.

3. A broach comprising a shank, teeth on 30 said shank having outer transverse cutting

edges, and means to guide said teeth into and through a previously formed slot in the stock, such means being narrower than said teeth.

4. A broach comprising a shank, teeth on said shank having outer transverse cutting edges, and a pilot on said shank ahead of said teeth, said pilot being narrower than said teeth.

5. A broach comprising a shank, teeth on said shank having outer transverse cutting edges, and a pilot attachable to said shank ahead of said teeth, said pilot being narrower than said teeth.

6. A broach comprising a shank, teeth attachable to said shank and having outer transverse cutting edges, and a pilot, of less width than that of said teeth, on said shank ahead of the teeth.

7. A broach comprising a shank, teeth attachable to said shank and having outer transverse cutting edges, and a pilot attachable to said shank ahead of said teeth, said pilot being narrower than said teeth.

8. A broach comprising a shank having longitudinal channels formed in the periphery and opening at the rear end of said shank, a row of teeth mounted on that part of said shank which is between said channels, and extending over the latter, and a pilot, of less width than said teeth, on said shank ahead of the teeth.

JOHN OAKLEY.
